Inventor:

James F. Steininger,

by Robert Burnet,

Attest,

UNITED STATES PATENT OFFICE.

JAMES F. STEININGER, OF CHICAGO, ILLINOIS.

ALTERNATING-CURRENT LIFTING MAGNET.

Application filed June 18, 1923. Serial No. 646,275.

To all whom it may concern:

Be it known that I, JAMES F. STEININGER, a citizen of the United States of America, residing at Chicago, in the county of Cook and State of Illinois, have invented a certain new and useful Improvement in Alternating-Current Lifting Magnets, of which the following is a specification.

This invention relates to the hand implement type of alternating current lifting and holding electro-magnets used in the separation of magnetic from non-magnetic scrap metal and the like, and has for its object:—

To provide a structural formation of the enclosing housing of an alternating current electro-magnet of the above described type, whereby undue heating of such housing by eddy currents generated or induced therein during continued actual use, is prevented in a simple and effective manner, all as will hereinafter more fully appear.

In the accompanying drawing:—

Fig. 1, is a longitudinal sectional elevation of a portable electro-magnet, embodying the present improvement.

Fig. 2, is a transverse sectional elevation on line 2.—2. Fig. 1 of the same.

Fig. 3, is a bottom view of the same.

Like reference numerals indicate like parts in the different views.

As represented in the drawing, the housing 1 which forms an enclosure for the laminated core 2, windings 3, and accessories is of an approximately rectangular shell shape, from the side walls of which extend a pair of opposed cheek plates 4 between the free ends of which a hand grip 5 is attached for convenience in handling the implement. One of said cheek plates 4 carrying a switch casing 6, in which the switch mechanism 7 by which current is conducted to the coils or windings 3, is controlled by a finger of the operator, as usual in the present class of hand implements.

The laminated core 2, is of the usual approximately U form, with the parallel portions or legs thereof surrounded by the coils or windings 3, and with the free ends of said legs extending through and a distance beyond the bottom wall of the housing 1 and in proper spaced relation to constitute projecting pole pieces adapted for insertion and movement through the metal scrap or

like material to be sorted into magnetic and non-magnetic portions.

A tubular inlet neck 8 is arranged at one side of the housing 1 for the passage of the usual cable conductor 9 by which electro-motive force is supplied to the windings 3 and switch mechanism 7 aforesaid.

The material part of the present improvement, in connection with the above described construction of alternating current electro-magnets, consists in the provision of a space, gap or opening 10, in the bottom wall of the enclosing housing 1, extending from one parallel member or leg to the other member or leg of the laminated core 2, and preferably at the mid-width of the same, as shown in Figs. 2 and 3.

Extended practical experiments have proven that the above described provision of the gap 10 acts to very effectively prevent the free flow of eddy and like currents induced in the metal of the housing 1, and the overheating of the same due to such free flow of said currents.

Having thus fully described my invention, what I claim as new and desire to secure by Letters Patent, is:—

1. In an alternating current electro-magnet, an enclosing casing of metal, a laminated core of an approximately U form arranged in said housing with the free ends of its legs projecting through a wall of the housing, and coils surrounding the legs of said core, the wall of the housing having a gap extending from core leg to core leg.

2. In an alternating current electro-magnet, an enclosing casing of metal, a laminated core of an approximately U form arranged in said housing with the free ends of its legs projecting through a wall of the housing and a distance beyond the same, and coils surrounding the legs of said core, the wall of the housing having a gap extending from core leg to core leg.

3. In an alternating current electro-magnet, an enclosing casing of metal, a laminated core of an approximately U form arranged in said housing with the free ends of its legs projecting through a wall of the housing, and coils surrounding the legs of said core, the wall of the housing having a gap extending from core leg to core leg at the midwidth of the same.

4. In an alternating current electro-magnet, an enclosing casing of metal, a laminated core of an approximately U form arranged in said housing with the free ends of its legs projecting through a wall of the housing and a distance beyond the same, and coils surrounding the legs of said core,

the wall of the housing having a gap extending from core leg to core leg at the midwidth of the same.

10

Signed at Chicago, Illinois, this 14th day of June, 1923.

JAMES F. STEININGER.
